UNITED STATES PATENT OFFICE.

HENRY H. HAMLETT, OF SALEM, MASSACHUSETTS.

POWER-PRESS.

No. 862,391.

Specification of Letters Patent.

Patented Aug. 6, 1907.

Application filed December 31, 1906. Serial No. 350,108.

To all whom it may concern:

Be it known that I, HENRY H. HAMLETT, a citizen of the United States, and a resident of Salem, in the State of Massachusetts, have invented a new and useful Improvement in Power-Presses, of which the following is a specification.

The nature of my invention consists in the improved construction and arrangement of parts whereby a safe and conveniently operated press is produced, as hereinafter set forth.

In the accompanying drawings, Figure 1 represents a side elevation of my improved power press. Fig. 2 represents the opposite side view. Fig. 3 represents a front view. Fig. 4 represents a rear view. Fig. 5 represents a top view. Fig. 6 represents a vertical section taken in the line 6 6 of Fig. 5. Fig. 7 represents an enlarged detail view of the clutch operating mechanism when the plunger of the press is in its lower position. Fig. 8 represents the same when the plunger of the press is in its upper position. Fig. 9 represents a detail top view of the clutch operating mechanism.

In the drawings, A represents the frame of the press, B the die, and C the plunger which projects from the plunger slide D held in the frame A, and actuated in the downward direction by means of the spiral spring E, held in the longitudinal perforation F. The spring E is attached at its lower end to the fixed eye G, and at its upper end to the cap H, which is secured to the end of the said plunger slide D, and the rear side of the said plunger slide is provided with the notch I. At the back of the plunger slide D is placed the sliding catch-bar J, provided with the pivoted catch K, which has its upper end pressed forward by means of the spiral spring L, and to the frame A at the back of the sliding catch-bar J is placed the catch-deflector W, pivoted to the frame A at the point M, and actuated for adjustment at its lower end by means of the screw N, the said deflector being provided with the incline O, which upon the upward movement of the sliding catch-bar J, will cause the disengagement of the catch K from the notch I of the plunger slide, thus allowing the action of the spring E to cause the rapid downward movement of the said plunger slide; and the outward or inward adjustment of the catch-deflector W, will serve to either increase or decrease the stroke of the plunger slide. The catch-bar J is operated by means of the crank A¹ and connecting rod B¹, the said crank being formed on the shaft C¹, which is operated from the driving shaft D¹ by means of the pinion E¹ and gear F¹, and upon the opposite end of the shaft C¹ from the gear F¹ is secured the ratchet wheel G¹, which is acted upon to prevent the backward rotation of the shaft C¹ by means of the pawl H¹, which latter is pivoted to the frame A of the machine at the point a.

55 The gear F¹ is loose upon the shaft C¹, the said shaft

being caused to revolve by the engagement of the teeth b of the sliding clutch member I¹ with the loose clutch member c at the hub of the gear F¹. The sliding clutch member I¹ may be operated for disengagement either by means of the hand lever J¹, which is pivoted to a bracket on the frame of the press, at the point d, and connected with the yoke M¹ of the said clutch-member at the joint e, or by means of the power-actuated lever K¹ which is pivoted to a bracket on the said frame at the point f. The lever K¹ passes loosely through a slot g, made in the end portion of the sliding bar L¹, which is rigidly connected with the yoke M¹ of the sliding clutch-member. The lever K¹ is connected by means of the links N¹ with the bell-crank lever O¹, which lever is pivoted at the point h to a plate P¹ of the frame, and the outer end of the said bell-crank lever is held in position for movement along the side of the said frame plate, by means of the guide bar Q¹.

Upon the pin i, to which the connecting rod B¹ is jointed, is loosely placed the pendent hook R¹ provided with the notch j adapted for engagement with the pin k at the outer end of the bell-crank lever O¹, as shown in Fig. 8, the curved form of the lower end of the said hook serving to cause it to swing automatically into the position for engagement.

At the side of the machine is journaled the hand operated arm l, by the movement of which the pendent hook R¹ may be forced out of its engagement with the pin k, and then the said bell-crank lever will drop to the position shown in Fig. 7, in which position the members of the driving clutch may by means of the hand lever J¹ be forced into engagement to cause the operation of the machine, and in this case upon the rotation of the crank A¹ and the consequent downward and subsequent upward movement of the catch-slide J, the notch j of the pendent hook R¹ will engage with the pin k of the bell-crank lever O¹ to cause the gradual disengagement of the members of the driving clutch, with the resulting stoppage of the operation of the machine at the completion of a single revolution, the automatic spring actuated operation of the press plunger having in the meantime been effected. And at this time the press will be securely locked against the subsequent accidental engagement of the members of the clutch, and the press can only be started into operation after the hook R¹ has been disengaged from the pin k, by the purposed inward movement of the arm l by the operator of the machine. But such disengagement and subsequent downward movement of the engaging arm of the bell-crank lever O¹ will not serve to cause the engagement of the driving clutch members, for there is left in the mechanism a sufficient amount of backlash at the links N¹, and at the slot g, to allow for such downward movement without affecting the clutch, thus leaving the clutch members to be actuated

into engagement by the hand of the operator upon the lever J^1 .

To the upper side o , of the bell-crank lever O^1 , is attached the spring m , which engages with the stop n , 5 and serves to check the upward movement of the said bell-crank lever, and retain the pin k in the notch j of the hook R^1 .

I claim as my invention:

1. The combination of the die, the plunger, the plunger slide, the sliding catch-bar for actuating the plunger slide to strike the blow, the pivoted catch adapted for engagement with the plunger slide, and the catch deflector with the crank shaft and connection between the crank shaft and the reciprocating catch-bar, for imparting reciprocating movement to the said catch-bar, the driven clutch member, the sliding clutch-member, the bell-crank lever connected with the said member and provided with the engaging pin, the pendent hook loosely connected with the sliding catch-bar and adapted for engagement with the pin of the bell-crank lever, to hold the sliding clutch member out of engagement with its opposite driven member at the completion of a single revolution of the crank-shaft.
2. The combination of the crank-shaft, the plunger slide, the reciprocating catch-bar and the catch, the driven clutch member, the sliding clutch-member, the bell-crank lever connected with the said sliding clutch member and provided with the engaging pin, the pendent hook loosely connected with the reciprocating catch-bar and adapted for engagement with the pin of the bell-crank lever to hold the sliding clutch member out of engagement with the opposite clutch member at the completion of a single revolution of the crank-shaft, and the hand operated arm for

causing the disengagement of the pendent hook from the pin of the bell-crank lever.

3. The combination of the crank-shaft, the plunger slide, 35 the reciprocating catch-bar, and the catch, the driven clutch member, the sliding clutch-member, the bell-crank lever connected with the said sliding clutch-member and provided with the engaging pin, the pendent hook loosely connected with the reciprocating catch-bar and adapted 40 for engagement with the pin of the bell-crank lever, to hold the sliding clutch-member out of engagement with the pin of the bell-crank lever at the completion of a single revolution of the crank-shaft, the hand operated arm for causing the disengagement of the pendent hook from the pin 45 of the bell-crank lever, and the hand lever for operating the sliding clutch-member into engagement upon the release of the pin of the bell-crank lever from the notch of the hook.

4. The combination of the crank-shaft, the plunger slide, 50 the reciprocating catch-bar, and the catch, the driven clutch member, the sliding clutch-member, the bell-crank lever connected with the said sliding clutch member and provided with the engaging pin, the pendent hook loosely 55 connected with the reciprocating catch-bar and adapted for engagement with the pin of the bell-crank lever, to carry the sliding clutch-member out of engagement with the driven clutch-member at the completion of a single revolution of the crank-shaft, and the spring and stop for limiting the upward movement of the arm of the bell-crank 60 lever.

HENRY H. HAMLETT.
